2 SHEETS—SHEET 2.

UNITED STATES PATENT OFFICE.

JUDD L. MINICK, OF ALTOONA, PENNSYLVANIA.

LAMP-FOCUSING DEVICE.

1,400,227.

Specification of Letters Patent. Patented Dec. 13, 1921.

Application filed February 19, 1920. Serial No. 359,950.

To all whom it may concern:

Be it known that I, JUDD L. MINICK, a citizen of the United States, and a resident of Altoona, in the county of Blair and State 5 of Pennsylvania, have invented certain new and useful Improvements in Lamp-Focusing Devices; and I do hereby declare the following to be a full, clear, and exact description of the invention, such as will enable 10 others skilled in the art to which it appertains to make and use the same.

This invention relates to improvements in lamp focusing devices.

In the ordinary manufacture of reflectors, 15 lenses, lamps and parts for mounting, there is liable to be imperfections which will interfere with and in fact prevent accurate alinement of the source of light with the center or focal point of the reflector, unless 20 some means be provided for effecting accurate adjustment of the parts after they shall have been assembled, and hence to obtain the highest efficiency, it is essential that accurate adjustment be made and maintained.

One object of my present invention is to provide simple and efficient means whereby the source of light (an electric or other type of lamp) may be accurately adjusted so that the center of the light source shall be set and 30 maintained at the "focal point" of the reflector or lens as the case may be.

With this and other objects in view, the invention consists in certain novel features of construction and combinations of parts 35 as hereinafter set forth and pointed out in the claims.

In the accompanying drawings; Figure 1 is a sectional view, partly in section, showing an embodiment of my invention; Fig. 2 is a 40 sectional view on the line 2—2 of Fig. 1; Fig. 3 is a front elevation of the framework and clamping device applied thereto; Fig. 4 is a side elevation of the structure shown in Fig. 3; Fig. 5 is a sectional view of the 45 shell 14; Fig. 6 is a view of one of the members of the cylinder 11; Fig. 7 a view of one of the members of the eccentric 7; Fig. 8 is a sectional view of the nut 20; Fig. 9 is an end view of the cylinder segment shown in Fig. 50 6; Fig. 10 is an end view of the eccentric segment shown in Fig. 7, and Fig. 11 is a diagrammatical view illustrating the method 55 of securing both vertical and transverse adjustment of the light source.

1 represents a frame or support comprising a pedestal 2 having an enlarged upper

end 3 providing a curved seat on which the lamp holding and adjusting devices are mounted, and an upright 4 having an annular upper end portion 5 which serves as supporting means for a reflector indicated by dotted lines at 6. While I have shown the parts 4, 5 as a convenient means for supporting a reflector, it will be understood that if a lens be employed instead of a reflector, or if 60 my improved focusing means be used for a motion picture machine, the parts 4 and 5 would be omitted.

An eccentric sleeve 7, viz., a sleeve having an eccentric bore,—comprising two or more 70 segments is supported on the curved seat at the upper end of the pedestal 2, and the eccentric sleeve is provided at one end with a knurled annular head 10 to facilitate manipulation of the same. Instead of making the 75 sleeve 7 in separate relatively movable sections, it may be made in a single piece instead so as to provide relatively movable portions. If desired, the two segments composing the eccentric sleeve 7 may be connected 80 by loosely fitting dowels 8 (Figs. 7 and 10) and said sleeve may be made with peripheral grooves 9 to receive flanges 9^a at the upper enlarged end of the pedestal, but these features of construction may be modified or 85 omitted without departing from the spirit of my invention.

A cylinder 11 is mounted to turn in the eccentric sleeve 7 and is provided at one end with an annular flange 12 overlying one end 90 of the sleeve 7; the other end of said cylinder being made with an annular knurled head 13 which occupies a position near the knurled head 10 of the eccentric sleeve. This cylinder may be made in separate relatively 95 movable sections or it may be made in a single piece and split to provide relatively movable portions.

Mounted within the cylinder 11, is a shell 14 (which may be split to provide relatively 100 movable portions) and one end of said shell is provided with an annular enlargement 15 provided with projections 16 at diametrically opposite points and these projections enter longitudinal grooves 17 in the inner 105 wall of the cylinder 11. The cylinder 11 is also provided near one end,—viz. within the annular head 13,—with a circular groove 18 which receives an annular flange 19 on a nut 20, the latter entering one end of said cylinder 110 and having a knurled part 21 disposed adjacent to the knurled head 13 of the cylin-

der. The nut 20 is made with a threaded bore to receive a threaded shank 22, the latter being rigidly secured to a socket piece 23. The socket piece 23 passes through the 5 split shell 14, and is made rigid therewith by means of a set screw 23^a or in any other suitable manner. The socket piece may project outwardly beyond the shell 14 and through the annular portion 5 of the frame-work, to receive and support a lamp 24.

In the drawings, I have illustrated my improvements as applicable for use as a locomotive head-light, and have illustrated an incandescent electric lamp as the source of 15 light, but it is evident that my invention is equally well adaptable for use on automobiles or other vehicles and that lamps, other than electric lamps might be employed.

A flexible metallic band 25 (which may be 20 termed a brake or clamping band) embraces the eccentric sleeve 7 between the grooves 9 and is rigidly secured near one end to the enlarged upper end 3 of the pedestal or base 2,—the other end of said band having secured thereto, a threaded rod 26 which passes freely through an opening 27 in the pedestal or support 2 and receives a nut 28. This nut is provided with a partly spherical portion 28^a which is seated within a similarly shaped recess 29 in a boss 29^a on the 30 pedestal or support, and thus the threaded rod 26 is permitted to seek and maintain proper alinement.

If the lamp be properly made and 35 screwed home in the socket piece, the longitudinal axis of the light source will be caused to coincide with the line $x-x$ Fig. 1 which, by properly adjusting the lamp focusing device, will be made to coincide 40 with the longitudinal axis of the reflector.

If the nut 20 be turned, the shell 14 in which the socket piece 23 is secured, will be moved longitudinally along the axis $x-x$,—the pins or projections 16 moving in the 45 grooves 17 preventing it from rotating about its axis,—and thus longitudinal adjustment of the source of light may be effected.

The diagram, Fig. 11, indicates a dia- 50 grammatic transverse section through the cylinder 11 and the eccentric sleeve 7, the part x being the projection of the axis $x-x$ of Fig. 1.

If the lamp were perfectly made and 55 screwed home in the socket piece 23, the longitudinal axis of the light source would coincide with the longitudinal axis of the reflector and hence vertical and transverse adjustment of the lamp would be unnecessary, but lamps, sockets and other parts are 60 not perfectly made and the center of the light source will not usually fall upon the point x ,—hence provision for such adjustments must be made, and this is accomplished by my improvements.

65 For the purpose of illustration, let it be

assumed that when the lamp is screwed home in the socket, the center of the light source falls at the point "L," and that it is desired to so adjust the lamp as to cause the point "L" to coincide with the point "x." 70 If the cylinder 11 be turned about its axis, the point "L" will describe a segment terminating at "M." If the eccentric sleeve 7 be turned about its axis, the point "M" will mark the segment terminating at "x." In 75 this particular instance, then, all that is necessary to be done in order to cause the point "L" to coincide with the point "x" is to turn the cylinder 11 until the point "L" coincides with the point "M," and then turn the eccentric sleeve until the point "M" coincides with the point "x."

When the lamp shall have been properly 80 adjusted, the parts will be clamped with the use of the clamping band 25 and the adjustment of the lamp will be maintained. It may be explained that slight tension on the band 25 will cause the eccentric sleeve 7 to be clamped, while the cylinder 11, shell 14 and nut 20 may remain free to adjust. Additional tension on the clamping band 25 will lock the cylinder 11 in addition to the eccentric sleeve 7, while further tension on said band will clamp or lock all the parts 85 securely together. The reverse action will 90 take place when the nut 28 for the clamping band is unscrewed.

The term "relatively movable portions" as applied to the sleeve 7, cylinder 11 and shell 14, is intended to comprehend the making of 100 each or any of these members in separate segments or in making each or any of said members in a single piece and split or slotted.

Various changes might be made in the 105 details of construction of my invention without departing from the spirit thereof or limiting its scope and hence I do not wish to restrict myself to the precise details herein set forth except as specified in the claims.

Having fully described my invention, what I claim as new and desire to secure by Letters-Patent is:—

1. In focusing means, the combination 115 with a support, of a sleeve having an eccentric bore and comprising relatively movable portions mounted on said support, a cylinder mounted in the eccentric bore of said sleeve and having relatively movable portions, a holder longitudinally movable in said cylinder, a lamp socket secured to said holder, and means for securing the parts in adjusted position.

2. In focusing means, the combination 120 with a support, of a sleeve having an eccentric bore and having relatively movable parts, revolvably mounted on said support, a cylinder revolvably mounted in the eccentric bore of said sleeve and having relatively 125 movable portions, means for holding a lamp 130

support in said cylinder, and a friction clamp embracing said sleeve for clamping the parts in adjusted position.

3. In focusing means, the combination with a support, of a sleeve having an eccentric bore, revolvably mounted on said support, said sleeve comprising a plurality of relatively movable portions, a cylinder revolvably mounted in the eccentric bore of said sleeve, said cylinder comprising a plurality of relatively movable portions, means for holding a lamp support in said cylinder, a clamping band secured to said first-mentioned support and embracing said sleeve, and means for tightening and loosening said band.

4. In focusing means, the combination with a support, of a sleeve having an eccentric bore, revolvably mounted on said support, a cylinder revolvably mounted in the eccentric bore of said sleeve, a shell longitudinally movable in said cylinder, means for preventing rotation of said shell relatively to the cylinder, a lamp support held in said shell and provided with a threaded shank, a nut revolvably connected with said cylinder and threaded on said shank, and means for holding said sleeve and cylinder in adjusted position.

5. In focusing means, the combination with a support, of a sleeve having an eccentric bore, revolvably mounted on said support and comprising relatively movable portions, a cylinder revolvably mounted in the bore of said sleeve and comprising relatively movable portions, a shell mounted to move longitudinally in said cylinder and comprising relatively movable portions, a lamp holder entering said shell and provided with a shank, means engaging said shank for effecting longitudinal adjustment of the shell, lamp holder and the lamp carried by the

latter, and means for holding the parts in adjusted position.

6. In focusing means, the combination with a support, of a sleeve having an eccentric bore, revolvably mounted on said support and comprising relatively movable portions, a cylinder mounted in the eccentric bore of said sleeve and comprising relatively movable portions, said cylinder having internal longitudinal grooves and an internal circular groove, a shell comprising relatively movable portions, entering said cylinder, projections on said shell movable in the longitudinal grooves in the cylinder, a nut having an annular flange movable in the circular groove in said cylinder, a lamp holder held in said shell and provided with a shank threaded through said nut, and a clamping band secured to said support, embracing said sleeve and adjustably connected with said support.

7. In a focusing means, the combination with a support provided with a part having a partly spherical socket, of a sleeve having an eccentric bore, revolvably mounted on said support, a cylinder revolvably mounted in the eccentric bore of said sleeve, means for holding a lamp support in said cylinder, a clamping band embracing said sleeve and secured at one end to said first-mentioned support, a threaded rod fixed to the other end of said band and passing through the socketed part of the first-mentioned support, and a nut on said rod having a partly spherical part seated in said partly spherical socket.

In testimony whereof, I have signed this specification in the presence of two subscribing witnesses.

JUDD L. MINICK.
